(57) **CLAIM**

The ornamental design for a table lamp, as shown and described.

DESCRIPTION

1. Table lamp
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Back view of state 1 of change
- 1.10 : Perspective view of state 1 of change
- 1.11 : Back view of state 2 of change
- 1.12 : Perspective view of state 2 of change
- 1.13 : Back view of state 3 of change
- 1.14 : Perspective view of state 3 of change
- 1.15 : Back view of state 4 of change
- 1.16 : Perspective view of state 4 of change
